UNITED STATES PATENT OFFICE.

HERMAN BENDER, OF NEW YORK, N. Y.

CHAIR.

1,159,158.

Specification of Letters Patent.

Patented Nov. 2, 1915.

Application filed October 22, 1914. Serial No. 868,077.

To all whom it may concern:

Be it known that I, HERMAN BENDER, a citizen of the United States, residing at New York, in the county of New York and State 5 of New York, have invented new and useful Improvements in Chairs, of which the following is a specification.

This invention relates to improvements in chairs, proposing a construction which is 10 especially useful in dry goods or women's furnishing stores in that the back may be utilized for the display of material or clothes.

The objects of the invention are to provide 15 a chair of the type stated in which the utilization of the back as a display stand or easel does not interfere with the normal use of the chair and does not require the occupant to move from the chair; to provide for 20 an effective display of material or clothes with the greatest convenience to the occupant of the chair; and to provide a chair for the purposes stated which shall be of simple, strong, and inexpensive structural 25 nature, and in which the back may be manipulated, as required, with ease and facility.

The above and other objects and advantages will appear as the description proceeds. 30

An embodiment of the invention is illustrated in the accompanying drawings, wherein:—

Figure 1 is a perspective view of a chair 35 in which the features of the invention are incorporated. Fig. 2 is a bottom plan view thereof. Fig. 3 is a longitudinal sectional view thereof, showing the back in position as a stand or easel for the display of materials or garments.

Similar characters of reference designate corresponding parts throughout the several views.

The chair proper is shown at 1 and may 45 be of any suitable construction. As shown it is in the form of a three-legged stool.

The essential feature of the invention is that the chair includes a back 2 which, in normal use, stands vertically or substantially vertically, at one side of the seat 1^a but which may be adjusted to a position slightly inclined above the horizontal, as shown in Fig. 3, in order to serve as a stand or easel for the effective and convenient display of materials or garments to the occupant of the chair.

The back 3 is supported from the seat by a hinge composed of straps 3 and 4 connected by an ordinary hinge joint 5, the strap 3 being rigidly secured to the back and the strap 4 being pivotally connected to the seat, as at 6, for movement in a horizontal plane parallel to the plane of the seat.

The strap 3 carries at its lower end a plate 7 having a co-planar finger 8 and an inwardly extending spring finger 9. The seat 1^a carries a bracket 10 having an edge recess 11 and the finger 8 normally engages in the recess 11 as shown in Figs. 1 and 2 in which relation the bracket 10 holds the back 2 in a vertical or substantially vertical position. The pressure exercised by the occupant of the chair against the back 2 causes the finger 8 to engage one of the inner sides of the recess 11 with sufficient force to prevent any accidental movement of the back about the pivot 6 as a center.

In order to utilize the back 2 as a stand or easel for the display of materials or garments, said back is moved through a prescribed arc about the pivot 6 as a center and the first consequence of this pivotal movement of the back is to disengage the finger 8 from the recess 11. At the completion of the pivotal movement of the back, the extent of which is approximately a third of a circle, the back is lowered to the position shown in Fig. 3, in which position it is inclined slightly above the horizontal and is at one side of the occupant of the chair. When the back is lowered, its downward movement is arrested by the engagement of the spring finger 9 against the underside of the seat 1^a, said finger thereby supporting said back in its lowered position.

The pivotal movement of the back in either direction is limited by the engagement of the strap 4 against shoulders 12 provided at the ends of an arcuate keeper 13 which is secured to the underface of the seat 1^a and is arranged under the hinge strap 4, engaging said hinge strap to prevent the same from sagging under the weight of the back.

The curvature of the keeper 13 is so selected that said keeper forms an abutment against which the finger 9 engages in the inclined position of the back 2 (see dotted lines, Fig. 2) and thereby prevents any accidental movement of the back when lowered about the pivot 6 as a center. To return the back to its normal vertical position

tion, it is necessary to first raise the back about the hinge joint 5 as an axis until the finger 9 clears the keeper 13 at which time, the back may be swung toward the bracket 10 until the finger 8 engages in the recess 11 of said bracket as above explained.

By moving the back 3 to a position at one side of the occupant of the chair when said back is to be utilized as a display stand or 10 easel, it is assured that the material or garments shall be shown in a position which is to the advantage of their display and at the same time is a most convenient one for the occupant of the chair.

15 The back may be easily and quickly manipulated from its vertical position at the back of the occupant to its inclined position at one side of the occupant and vice versa and is reliably held in either of its 20 operative positions as will be clear from the foregoing description.

Having fully described my invention, I claim:—

1. In combination, a chair seat, a back 25 therefor, a hinge connection between said seat and back including a pair of hingedly connected straps one of which is fixed to the back and the other of which is pivoted to the seat adjacent the under face thereof for 30 movement in a plane parallel thereto, a bracket fixed to the seat, means carried by the back for engagement with the bracket to sustain the back in a vertical position, and means carried by the back for engagement 35 with the under face of the seat to sustain the back in an inclined position located at a distance from the position which the back occupies when it is vertically disposed.

2. In combination, a chair seat, a back 40 therefor, a hinge connection between said seat and back comprising a pair of hingedly connected straps one of which is fixed to the back and the other of which is pivoted to the seat adjacent the under face thereof 45 for movement in a plane parallel thereto, a bracket carried by the seat and having an edge recess, and a finger carried by the back for engagement in said edge recess, the seat being movable to a position wherein said 50 finger is disengaged from said edge recess and in such position being movable to a plane inclined slightly above the horizontal.

3. In combination, a chair seat, a back 55 therefor, a hinge connection between said seat and back comprising a pair of hingedly connected straps one of which is fixed to the back and the other of which is pivoted to the seat adjacent the under face thereof for movement in a plane parallel thereto, a 60 bracket carried by the seat and having an edge recess, a finger carried by the back for engagement in said edge recess, the seat being movable to a position wherein said finger is disengaged from said edge recess 65 and in such position being movable to a

plane inclined slightly above the horizontal, and a second finger carried by the back to engage the under face of the seat and support the back in said inclined position thereof.

4. In combination, a chair seat, a back therefor, a hinge connection between said seat and back comprising a pair of hingedly connected straps one of which is fixed to the back and the other of which is pivoted to the seat adjacent the under face thereof for movement in a plane parallel thereto, a bracket carried by the seat and having an edge recess, a finger carried by the back for engagement in said edge recess, the seat being movable to a position wherein said finger is disengaged from said edge recess and in such position being movable to a plane inclined slightly above the horizontal, a second finger carried by the back to engage the under face of the seat and support the back in said inclined position thereof, and means carried by the seat and against which said last-named finger engages to prevent pivotal movement of the seat when the latter is disposed in said inclined plane.

5. In combination, a chair seat, a back therefor, a hinge connection between said seat and back comprising a pair of hingedly connected straps one of which is fixed to the back and the other of which is pivoted to the seat adjacent the under face thereof for movement in a plane parallel thereto, a bracket carried by the seat and having an edge recess, a finger carried by the back for engagement in said edge recess, the seat being movable to a position wherein said finger is disengaged from said edge recess and in such position being movable to a plane inclined slightly above the horizontal, a second finger carried by the back to engage the under face of the seat and support the back in said inclined position thereof, and a keeper secured to the seat and fitted over the pivotally mounted hinge strap to prevent sagging thereof under the weight of the seat and to provide end stops therefor, the keeper being formed to provide an abutment against which said last-named finger engages when the seat is positioned in an inclined plane.

6. In combination, a chair seat, a back, means supporting the back from the seat and constructed to provide for a pivotal movement of the back in the direction of the periphery of the seat and for a pivotal movement of the back at an angle to the plane of the seat, means located at one point of the periphery of the seat to support the back in a substantially vertical position, and other means to support the seat in an inclined plane at another point along the periphery of the back.

7. In combination, a chair seat, a back, means supporting the back from the seat

and constructed to provide for a pivotal movement of the back in the direction of the periphery of the seat and for a pivotal movement of the back at an angle to the plane of the seat, means located at one point of the periphery of the seat to support the back in a substantially vertical position, other means to support the seat in an inclined plane at another point along the periphery of the back, and means to prevent movement of the seat in the direction of the periphery of the back when the seat is disposed in said inclined plane.

8. In combination, a chair seat, a back, means supporting the back from the seat and constructed to provide for a pivotal movement of the back in the direction of the periphery of the seat and for a pivotal movement of the back at an angle to the plane of the seat, and means located at one point of the periphery of the seat to support the back in a substantially vertical position.

9. In combination, a chair seat, a back, means supporting the back from the seat and constructed to provide for a pivotal movement of the back in the direction of the periphery of the seat and for a pivotal

movement of the back at an angle to the plane of the seat, and means including companion elements carried by the back and the seat to support the back in a substantially vertical position at a fixed point along the periphery of the seat.

10. In combination, a chair seat, a back, means supporting the back from the seat and constructed to provide for a pivotal movement of the back in the direction of the periphery of the seat and for a pivotal movement of the back at an angle to the plane of the seat, means including companion elements carried by the back and the seat to support the back in a substantially vertical position at a fixed point along the periphery of the seat, and other means carried by the back and engageable with the seat at another point along the periphery thereof to support the back in an inclined plane.

In testimony whereof I have hereunto set my hand in presence of two subscribing witnesses.

HERMAN BENDER.
